Primary Examiner—Susan J. Lucas*Assistant Examiner*—Jennifer A. Regester*Attorney, Agent, or Firm*—Boniard L. Brown[57] CLAIM

The ornamental design for a dispenser for matches, as shown and described.

DESCRIPTION

FIG. 1 is a perspective view of a dispenser for matches, showing my new design;

FIG. 2 is a side elevational view thereof;

FIG. 3 is a front view thereof;

FIG. 4 is a side elevational view thereof, opposite to that shown in FIG. 2;

FIG. 5 is rear view thereof;

FIG. 6 is a top view thereof; and,

FIG. 7 is bottom view thereof.

The broken line showing of a matchbox and matches in FIG. 1 are for illustrative purposes only and form no part of the claimed design.
